UNITED STATES PATENT OFFICE.

ELLIS L. CASTOR, OF READING, PENNSYLVANIA.

SHUTTLE.

SPECIFICATION forming part of Letters Patent No. 731,856, dated June 23, 1903.

Application filed July 29, 1902. Serial No. 117,561. (No model.)

To all whom it may concern:

Be it known that I, ELLIS L. CASTOR, a citizen of the United States, residing at Reading, in the county of Berks and State of Pennsylvania, have invented new and useful Improvements in Shuttles, of which the following is a specification.

My invention relates to shuttles, and more particularly to means for holding bobbins in shuttle-bodies, and its novelty, utility, and practical advantages will be fully understood from the following description and claims when taken in conjunction with the accompanying drawings, in which—

15 Figure 1 is a plan view of a portion of a shuttle embodying my improved bobbin-holder, the said holder being shown with a bobbin in proper position therein. Fig. 2 is a longitudinal section of the same with a portion of the fixed jaw of the bobbin-holder broken away. Fig. 3 is a transverse section taken in the plane indicated by the broken line 33 extending through Figs. 1 and 2. Fig. 4 is a transverse section taken in the plane indicated by the broken line 44 extending through Figs. 1 and 2, with a portion of the bobbin-head broken away; and Fig. 5 comprises disconnected perspective views of the jaws and other parts making up my improved 30 bobbin-holder.

Similar letters of reference designate corresponding parts in all of the several views of the drawings, referring to which—

A is a shuttle-body, recessed at A' in the usual manner to receive a bobbin B, having a circumferential groove a in its head b, and C is my improved bobbin-holder. This holder in the present and preferred embodiment of my invention comprises a fixed jaw D, a pivoted jaw E, a retainer F for holding the jaw E against casual movement when said jaw is in its lower position and also when it is in its upper position, and a spring G, which backs the retainer and tends to press the same forwardly. The jaw D is disposed transversely in the bobbin-receiving recess A' of the shuttle-body at one end thereof and is crescent or C shaped, as best shown in Fig. 5. It is provided at its forward edge with an inwardly directed flange c, which extends throughout the length of said edge, so as to enter the groove a in the bobbin-head at the bottom

and sides of said head, and is also provided with a rearwardly-extending shank d of channel form in cross-section. This latter is arranged in a recess e in the body A between the bottom of said recess and horizontal flanges f on the body, as best shown in Figs. 1, 3, and 4.

As best shown in Figs. 2 and 4, the jaw E of the bobbin-holder is curved in cross-section to conform to the head of the bobbin and is provided at its forward edge with an inwardly-directed flange g, designed to enter the groove a in the bobbin-head at the upper side of said head. Said jaw E is also provided with a depending portion h, which is arranged in the shank d of the fixed jaw D and is pivotally connected to the shank and the shuttle-body by a transverse pintle i. The portion h of the pivoted jaw terminates at its rear end in a rounded head j, which is disposed in the concave forward side of the retainer F after the manner best shown in Fig. 2. The retainer is backed by the spring G and is preferably provided with a rearwardly-extending stem k, arranged in the spring, as illustrated. The spring G exerts pressure in a forward direction against the retainer F and by so doing enables the retainer to securely hold the jaw E against casual movement when the forward portion of said jaw is pulled upwardly and also when the forward portion of the jaw is pushed downwardly. The spring also assists in the downward movement of the forward portion of the jaw E after such movement is started.

When a bobbin is placed in the recess A' of the shuttle-body A, so that the flange c of jaw D enters the groove a at the bottom and opposite sides of the bobbin-head, and the forward portion of the jaw E is pushed downwardly, so that its flange g enters the groove a at the upper side of the bobbin-head, it will be seen that the jaw E will be securely retained against casual movement in said position, and in consequence the bobbin being engaged by the jaws D E at all sides will be securely clamped and held by the same. It will also be observed that the bobbin will be held firm—*i. e.*, in such manner as to prevent movement thereof in the shuttle-body—which is highly desirable in weaving. To effect the removal of the bobbin from the shuttle-body,

an attendant has but to move the free end of the bobbin upwardly. When the bobbin is thus moved, the bobbin-head presses the jaw E up into its upper position, where it will be held by the retainer F, and the bobbin may then be readily withdrawn from the shuttle-body.

The fixed jaw D of my improvements is susceptible of being used alone in a spindle-
10 shuttle for the purpose of holding a bobbin, the spindle being provided on the jaw E in lieu of the curved and flanged portion or otherwise mounted in the shuttle-body.

I have entered into a detailed description
15 of the construction and relative arrangement of parts embraced in the present and preferred embodiment of my invention in order to impart a full, clear, and exact understanding of the same. I do not desire, however,
20 to be understood as confining myself to such specific construction and arrangement of parts, as such changes or modifications may be made in practice as fairly fall within the scope of my claims.

25 Having described my invention, what I claim, and desire to secure by Letters Patent, is—

1. In a shuttle, the combination of a body recessed to receive a bobbin, and a bobbin-
30 holder carried by the body, and comprising a crescent or C shaped jaw fixed transversely in the lower portion of the recess of the body,

and having a flanged forward edge arranged to engage a circumferential groove in a bobbin-head at the bottom and opposite sides of 35 said head, a jaw pivoted at an intermediate point of its length and having a transversely curved and flanged forward portion, and a rounded head on its rear portion, and a spring-backed retainer having a concave forward 40 side receiving said rounded head.

2. In a shuttle, the combination of a body recessed to receive a bobbin, and a bobbin-holder carried by the body, and comprising the crescent or C shaped jaw fixed transversely in the lower portion of the recess of the body at one end thereof, and having the flanged forward edge, and also having the rearwardly-extending shank of channel form, the jaw having the forward transversely 50 curved and flanged portion, and the depending portion pivoted in the shank of the fixed jaw, and also having the rounded head at the rear of said depending portion, the retainer receiving said head, and the spring 55 backing said retainer.

In testimony whereof I have hereunto set my hand in presence of two subscribing witnesses.

ELLIS L. CASTOR.
